DESIGN FOR A HEEL

Walter Schwartz, New York, N. Y., assignor to New York Progressive Wood Heel Corporation, Brooklyn, N. Y., a corporation of New York

Application April 14, 1937, Serial No. 68,753

Term of patent 14 years

To all whom it may concern:

Be it known that I, Walter Schwartz, a citizen of the United States, residing in New York, county of New York, and State of New York, have invented a new, original, and ornamental Design for a Heel, of which the following is a specification, reference being had to the accompanying drawing, forming a part thereof.

In the drawing:—

Fig. 1 is a perspective view of the top and sides of a heel showing my new design.

Fig. 2 is a perspective view showing the heel viewed from the bottom.

Fig. 3 is an end elevation of the heel shown in Fig. 1.

I claim:—

The ornamental design for a heel as shown.

WALTER SCHWARTZ.
